Primary Examiner—Elizabeth A. Albert(74) *Attorney, Agent, or Firm*—Lerner, David, Littenberg, Krumholz & Mentlik, LLP(57) **CLAIM**

The ornamental design for a double handled clipboard, as shown and described.

DESCRIPTION

FIG. 1 is a top plan view of a double handled clipboard, in accordance with the present invention.

FIG. 2 is a front plan view of the double handled clipboard shown in FIG. 1.

FIG. 3 is a right side elevational view of the double handled clipboard shown in FIG. 2.

FIG. 4 is a rear plan view of the double handled clipboard shown in FIG. 2; and,

FIG. 5 is a front isometric view of the double handled clipboard shown in FIG. 2.

The broken lines showing the hinge structure in FIGS. 1 and 3 of the drawings are for informational purposes only and form no part of the claimed design.
